UNITED STATES PATENT OFFICE
FRED ASHWORTH, OF BEVERLY, MASSACHUSETTS, ASSIGNOR TO UNITED SHOE MACHINERY CORPORATION, OF PATERSON, NEW JERSEY, A CORPORATION OF NEW JERSEY
SEWING MACHINE

Application filed January 4, 1930. Serial No. 418,545.

The present invention relates to sewing machines, and is herein shown as embodied in a shoe sole sewing machine of the so-called McKay type, the stitch-forming devices of which comprise a straight hook needle, and the work support of which consists of a rotatable horn arranged to extend within the shoe and provided at its tip with a needle threading device or whirl for laying the thread in the hook of the needle.

The invention is intended primarily as an improvement in the stopping and presser-foot lifting devices of the McKay shoe sewing machines disclosed in the patent to Bernard T. Leveque No. 1,738,778 dated December 10, 1929, and in the application of Bernard T. Leveque Serial No. 169,203 filed February 18, 1927 although, except as defined in the claims, the features of the invention are not limited to use in these particular machines, but may be embodied in other sewing machines in which means are provided for disconnecting the needle from its actuating mechanism and for lifting the presser-foot upon stopping the machine.

Each of the machines of the Leveque patent and application, above referred to, is provided with means which is thrown into operation upon stopping the machine to render inoperative the connections between the needle and the actuating cam or sewing shaft, so as to cause the needle to stop at the limit of its upward stroke. The machine of the patent is also provided with mechanism acting upon stopping the machine to lift the presser-foot from the work, and the machine of the Leveque application is provided with an improved and simplified mechanism for accomplishing the same result. In both of these machines, and in any machine provided with mechanism for disconnecting the needle from its actuating mechanism and for lifting the presser-foot upon stopping, it is desirable that the needle be stopped in its upper position before the presser-foot is raised in order

that the thread of the last stitch may be properly drawn into the work, and that the work may not be perforated by the needle after having been released by the presser-foot. The mechanisms of the Leveque machines were intended to produce this result, but in operation and particularly in the operation of the simplified mechanism of the Leveque application, it has been found that occasionally upon stopping, the presser-foot will be lifted before the disconnection of the needle, and as a consequence, the final stitch or stitches of the seam are not properly formed and a bunch of thread is formed at the end of the stitching. The primary object of the present invention is to improve the mechanism of the Leveque application for disconnecting the needle from its actuating mechanism and for lifting the presser-foot at the end of the sewing so as to insure a delay in the lifting of the presser-foot until after the needle has been brought to rest. Other objects of the invention are to improve the construction, arrangement and mode of operation of the various parts of mechanisms which may be utilized in disconnecting the needle of a sewing machine from its actuating mechanism, and for raising the presser-foot upon stopping the machine.

With the above objects in view, the present invention consists in the constructions, combinations, and arrangements of parts herein-after described and claimed, the advantages of which will be obvious to those skilled in the art from the following description taken in connection with the accompanying drawings in which Fig. 1 is a view in front elevation of the head of a lock-stitch McKay type shoe sewing machine; Fig. 2 is a detail view in side elevation of a portion of the mechanism shown in Fig. 1, illustrating particularly the mechanism for lifting the presser-foot and for controlling its action from the needle disconnecting mechanism; and Fig. 3 is a detail sectional view taken on the line 3-3.

of Fig. 2, and showing in dot and dash lines the latch actuating arm of the needle disconnecting mechanism.

Except as hereinafter described, the machine illustrated in the drawings is the same in the construction, arrangement and mode of operation of its various parts as the machine disclosed in the application of Bernard T. Leveque hereinbefore referred to. The main cam shaft or, as it may conveniently be termed, sewing shaft, is indicated at 4, and is driven from a motor in the base of the machine through a clutch which is controlled from a starting and stopping treadle, as in the machine of the Leveque application, and also as in the machine of the Leveque patent. The straight hook needle of the machine is indicated at 6 and is secured to the lower end of the needle bar 8 mounted to reciprocate vertically in bearings in the head of the machine. This needle bar is actuated from the sewing shaft 4 through connections which include the two levers 10 and 12, which levers are pivotally mounted concentrically with each other at one end, and at their other ends are adapted to be connected together by a latch 14 pivotally mounted upon the lever 12 and arranged to engage a pin 16 on the lever 10. The lever 10 is provided midway its length with a curved slot 18 which is engaged by a crank pin 20 on the forward end of the sewing shaft 4, and the lever 12 is connected by means of a link 22 to a block 24 clamped to the needle bar 8. The levers 10 and 12 are connected by a coiled spring 26 at the pivotal axis of the levers, which spring tends to hold the levers in the position indicated in Figure 1 with the blocks 28 and 30 on the levers abutting and with the pin 16 in position to be engaged by the latch 14. The construction and arrangement of the levers 10 and 12 and of the latch 14 and pin 16 are the same as in both of the Leveque machines hereinbefore referred to, and provides a simple and efficient mechanism for actuating the needle from the sewing shaft while permitting the needle to be disconnected from the sewing shaft by an actuation of the latch 14 to release the pin 16.

Upon stopping the machine, the needle is disconnected from the sewing cam shaft as the needle bar reaches the top of its stroke, and in order to accomplish this result, a slotted arm 32 is provided, the slot 34 in which engages a pin 36 secured to the lever 12, concentric with the pivot of the latch 14. The upper end of the slot 34 extends laterally to the right, as viewed in Figures 1 and 3, and the arrangement is such that as the needle bar reaches the limit of its upward movement, the pin 36 comes in line with this laterally extending portion of the slot. With the parts in this position, a lateral movement of the upper end of the lever 32 to the left, as viewed in Figure 1, is permitted, and such movement brings a pin 38 in the upper end of

the lever 32 against the upwardly projecting tail 40 of the latch 14, and swings the latch against the tension of its spring 42 in a direction to release the pin 16 on the lever 10, thereby permitting the continued rotation of the sewing shaft, while the needle bar remains locked in its upward position by the engagement of the pin 36 with the horizontal portion of the slot 34. To cause the arm to be pressed yieldingly towards the right, as viewed in Figure 1, and thus prevent actuation of the arm to disconnect the needle from the sewing shaft during the sewing of a seam, the arm is rigidly connected to the forward end of a rock shaft 44, the rear end of which is provided with an arm 46 connected by a link 48 to an arm 50 loosely mounted upon a shaft 52 and connected thereto by a coiled spring 54. Through the connections described, the spring 54 acts to hold the arm 32 yieldingly toward the right while the machine is in operation. To render inoperative the actuating connections between the sewing shaft and the needle bar, and thereby disconnect the needle from the shaft, connections are provided, as in the machines of the Leveque patent and application, through which the arm 32 is moved to the left to disconnect the latch 14 from the pin 16 when the starting and stopping treadle is actuated to stop the machine. These connections comprise an arm 56 fast to the shaft 52, a rod 58 connecting this arm to the starting and stopping treadle, a lug 59 projecting laterally from the arm 56 beneath a rearward extension 61 of the arm 50, and a heavy spring, not shown in the drawings, surrounding the shaft 52 and tending to turn the shaft in a clockwise direction, as viewed in Figure 2. With this construction, when the starting and stopping treadle is permitted to rise, the lug 59 on the arm 56 engages the extension 61 on the arm 50, and the heavy spring above referred to acting through the shaft 52 and arm 50, exerts a pressure on the arm 32 which holds the right hand side of the slot 34, as viewed in Figure 1, against the pin 36 on the lever 12. As soon as the pin reaches the upper portion of the slot 34 therefor the arm 32 will be moved to the left, as viewed in Figure 1, the pin 36 entering the horizontal portion of the slot and thereby locking the needle at the limit of its upward stroke and the pin 38 engaging the tail 40 of the latch 14, and disengaging the latch from the pin 16 on the lever 10 which is permitted to continue in its movement during the continued rotation of the sewing shaft.

In the machines of the Leveque patent and application the arm corresponding to the slotted arm 32 of the present construction was also utilized as a portion of the feeding mechanism, the vertical portion of the slot in the arm being shaped to cause the desired oscillating movements to be imparted to the

arm as the pin 36 moves up and down in the slot during the operation of the machine in sewing a seam. In the present construction, the arm 32 is utilized merely to disengage the latch 14 from the pin 16, an additional arm 33 being provided for actuating the work feeding device, which arm is loosely mounted upon the shaft 44 and provided with a suitably shaped slot engaged by the pin 36 on the lever 12.

The presser-foot of the machine is indicated at 60, and is secured to a block 62 fast on the lower end of a vertically movable spring pressed presser-foot bar 64. This presser-foot bar is raised and lowered during each stitch-forming cycle of the machine by mechanism disclosed in the patent and application of Leveque hereinbefore referred to. To lift the presser-foot upon stopping the machine, and after the needle has been disconnected from its actuating mechanism and stopped at the limit of its upward movement, a presser-foot lifting member indicated at 66 is provided. This member is similar to the corresponding presser-foot lifting member of the mechanism disclosed in the Leveque application. This member is supported from the sewing shaft 4 and hangs vertically from the shaft, its upper end being formed as an eccentric strap surrounding an eccentric 68 on the shaft, from which a constant vertical reciprocation is imparted to the member while the sewing machine is in operation. At its lower end, this presser-foot lifting member is provided with a projection 70 which is adapted to engage a lug 71 projecting laterally from an arm 72 fast on the rock shaft 74. The rock shaft 74 is provided at its forward end with the arm 76 connected by a link 78 to the block 62 at the lower end of the presser-foot bar 64 and the arrangement of the arms 72 and 76 is such that an upward movement of the arm 72 produces a corresponding movement of the arm 76 and lifts the presser-foot from the work. While the machine is in operation, the presser-foot lifting member 66 is held in a position in which the lug 71 is out of the path of movement of the projection 70. During the stopping of the machine, however, the presser-foot lifting member is moved into the position indicated in Figure 3, and during its upward movement acts to rock the shaft 74 by the engagement of the projection 70 with the lug 71, and lift the presser-foot.

After the presser-foot is raised, the sewing shaft 4 continues to rotate through one or more revolutions, and in order to retain the presser-foot in its raised position, a retaining member in the form of a latch is provided arranged to engage a lug projecting laterally from the arm 72 in the opposite direction from the lug 71. This retaining member is similar to the corresponding re-

taining member of the mechanism disclosed in the Leveque application and is indicated at 80. This retaining member is supported in a vertical position from the sewing shaft 4 at the side of the presser-foot lifting member, and is provided at its lower end with a projection 82 adapted to engage a lug on the arm 72. The retaining member 80 has no vertical movement but is arranged to swing about the shaft 4 of the pivot to move its projection 82 into and out of a position to engage the lug on the arm 72.

After the needle has been disconnected from the sewing shaft and after the presser-foot has been lifted and the rotation of the sewing shaft has stopped, the parts are in the relative positions indicated in Figure 3. In starting the machine again into operation, it is necessary to move the retaining latch out of engagement with the arm 72 to permit the presser-foot to drop upon the work, and it is also necessary to move the presser-foot lifting member 66 to a position in which the lug 71 on the arm 72 will not be engaged by the lifting member during its reciprocation. In the construction disclosed in the Leveque application, both the presser-foot lifting member and the retaining member are controlled during the starting of the machine by an arm corresponding to the arm indicated at 84 fast upon the rock shaft 52. Also, in the mechanism disclosed in the Leveque application, the arm corresponding to the arm indicated at 84 is utilized to control the movements of both the presser-foot lifting member and the retaining member in stopping. With this construction, it was sometimes found to be difficult, if not impossible, to assemble the parts or to adjust them after being assembled so as to insure during the stopping of the machine, the disconnection of the needle from the sewing shaft by the movement of the arm 32 before the presser-foot lifting and retaining members were allowed to move into a position to raise and retain the presser-foot. This defect in the operation of the machine of the Leveque application becomes more apparent as the parts become worn or disarranged in use. To overcome this defect, the present construction utilizes the arm 84 to control the position of the retaining latch member 80 only and provides a separate direct connection from the latch operating arm 32 to the presser-foot lifting member 66 so that the presser-foot lifting member is directly controlled from the arm which acts to disconnect the needle from the sewing shaft, and any possibility of the raising of the presser-foot taking place before the disconnection of the needle is absolutely prevented regardless of slight inaccuracies in assembling the various parts or of wear or looseness in the connections through which the arm for disconnecting the needle is actuated. As illustrated in the drawings, the arm 84 on the

shaft 52 is arranged as in the mechanism of the Leveque application, to engage a cam surface formed on the retaining latch 80, the arrangement being such that as the shaft 52 is positively actuated from the treadle in starting the machine, the latch 80 is positively moved out of engagement with the arm 72 to permit the presser-foot to drop upon the work before the needle is connected to its actuating mechanism, and during the movement of the shaft 52 in the reverse direction in stopping the machine, the retaining latch 80 is allowed to move into a position to retain the arm 72 as soon as it is raised by the lifting member 66. To control the position of the lifting member 66, however, an arm 86 is rigidly secured to the rock shaft 44 carrying the arm 32 and is connected by a rod 88 to the lower end of the lifting member 66, the rod being pivotally connected at one end to the lower end of the lifting members 66 and at its other end passing transversely through the projecting end of a pin 90 rotatably mounted in the lower end of the arm 86. To provide a yielding engagement of the lifting member with the lug 71 on the lever 72 and insure the proper engagement of the lug 70 with the lug 71, a spring 92 is coiled around the rod 88 and is interposed between the pin 90 and a shoulder near its pivotal connection with the lifting member. To insure a positive withdrawal of the presser-foot lifting member to a position where its lug 70 cannot engage the lug 71, a cross pin 94 is mounted in the end of the rod 88 in position to be engaged by the pin 90 when the arm 86 is actuated to move the lifting member away from the lug 71.

As a convenient means cooperating with the arm 84 to control the position of the presser-foot retaining member 80, a rod 96 is pivotally connected to the lower end of the member 80 and passes through the end of the pin 90 on the opposite side of the arm 86 from the pin 88, which rod 96 forms a support for a spring 98 coiled around the rod and interposed between the pin 90 and a shoulder near the pivoted end of the rod.

The nature and scope of the invention having been indicated and an embodiment of the invention having been specifically described, what is claimed is:

1. A sewing machine having, in combination, stitch-forming devices including a needle, a presser-foot, a sewing shaft, actuating connections between said shaft and needle, a treadle controlled member for rendering said connections inoperative, and presser-foot lifting mechanism controlled directly by said member to lift the presser-foot only after said connections have been rendered inoperative.

2. A sewing machine having, in combination, stitch-forming devices including a needle, a presser-foot, a sewing shaft, actuating

connections between said shaft and needle, a treadle controlled member for rendering said connections inoperative, presser-foot lifting mechanism, and means actuated directly by said member to render said connections inoperative, and thereafter to cause said presser-foot lifting mechanism to lift the presser-foot.

3. A sewing machine having, in combination, stitch-forming devices including a needle, a presser-foot, a sewing shaft, actuating connections between said shaft and needle including two members and a connecting latch, a latch actuating arm movable to actuate the latch to render said connections inoperative, a presser-foot lifting mechanism including a reciprocating presser-foot lifting device driven continuously by the sewing shaft and a member adapted to be engaged by said device to lift the presser-foot, and a direct connection from said arm to the presser-foot lifting device for moving the lifting device into engagement with said member to cause the presser-foot to be lifted after the actuation of the latch.

4. A sewing machine having, in combination, stitch-forming devices including a needle, a presser-foot, a sewing shaft, actuating connections between said shaft and needle, a presser-foot lifting mechanism including a reciprocating presser-foot lifting device driven continuously by the sewing shaft, and a member connected to the presser-foot adapted to be engaged by said device to lift the presser-foot, a latch arranged to engage said member and hold the presser-foot raised during the continued rotation of the sewing shaft, a treadle controlled member for rendering the connections between the sewing shaft and needle inoperative, a direct connection between said treadle controlled member and the presser-foot lifting device for moving the lifting device into engagement with the member connected to the presser-foot to cause the presser-foot to be lifted after the connections between the sewing shaft and needle have been rendered inoperative, and treadle actuated means for actuating the latch to release the presser-foot.

5. A sewing machine having, in combination, stitch-forming devices including a needle, a presser-foot, a sewing shaft, actuating connections between said shaft and needle including two members and a connecting latch, a latch actuating arm movable to actuate the latch to render said connections inoperative, a presser-foot lifting mechanism including a reciprocating presser-foot lifting device driven continuously by the sewing shaft, and a member connected to the presser-foot adapted to be engaged by said device to lift the presser-foot, an arm rigid with the latch actuating arm, a connection from said last mentioned arm to the presser-foot lifting device for moving the lifting de-

vice into engagement with the member connected to the presser-foot to cause the presser-foot to be lifted after the connections between the sewing shaft and needle have been rendered inoperative, and means for retaining the presser-foot in the position to which it is lifted during the continued rotation of the sewing shaft.

In testimony whereof I have signed my
10 name to this specification.

FRED ASHWORTH.
